US00D715837S

(12) **United States Design Patent**
Höhne

(10) **Patent No.:** **US D715,837 S**
(45) **Date of Patent:** **** Oct. 21, 2014**

(54) **DISPLAY SCREEN OR PORTION THEREOF
WITH GRAPHICAL USER INTERFACE**

(71) Applicant: **Apple Inc.**, Cupertino, CA (US)

(72) Inventor: **Sascha Höhne**, Hamburg (DE)

(73) Assignee: **Apple Inc.**, Cupertino, CA (US)

(**) Term: **14 Years**

(21) Appl. No.: **29/434,608**

(22) Filed: **Oct. 15, 2012**

Related U.S. Application Data

(63) Continuation of application No. 29/414,899, filed on Mar. 5, 2012, now abandoned.

(51) **LOC (10) Cl.** **14-04**

CLAIM

The ornamental design for a display screen or portion thereof with graphical user interface, as shown and described.

DESCRIPTION

The FIGURE is a front view of a display screen or portion thereof with graphical user interface showing my new design. The broken lines around the FIGURE showing a display screen or portion thereof form no part of the claimed design.

1 Claim, 1 Drawing Sheet
